(57) **CLAIM**

The ornamental design for a table, as shown and described.

DESCRIPTION

FIG. 1 is a perspective view of a table showing my new design.

FIG. 2 is a front view of my new design shown in FIG. 1.

FIG. 3 is rear view of my new design shown in FIG. 1.

FIG. 4 is a right-side view of my new design shown in FIG. 1.

FIG. 5 is a left-side view of my new design shown in FIG. 1.

FIG. 6 is a top view of my new design shown in FIG. 1; and, FIG. 7 is a bottom view of my new design shown in FIG. 1. The broken lines showing the remaining portions of the table illustrate features of the article of manufacture that form no part of the claimed design.
